J. C. GLENN,
DEWATERING MECHANISM FOR PAPER MACHINE DRUMS.
APPLICATION FILED JAN. 5, 1920.

1,374,198.

Patented Apr. 12, 1921.

UNITED STATES PATENT OFFICE.

JOHN C. GLENN, OF ERIE, PENNSYLVANIA.

DEWATERING MECHANISM FOR PAPER-MACHINE DRUMS.

1,374,198.

Specification of Letters Patent.

Patented Apr. 12, 1921.

Application filed January 5, 1920. Serial No. 349,358.

To all whom it may concern:

Be it known that I, JOHN C. GLENN, a citizen of the United States, residing at Erie, in the county of Erie and State of Pennsylvania, have invented certain new and useful Improvements in Dewatering Mechanism for Paper-Machine Drums; and I do hereby declare the following to be a full, clear, and exact description of the invention, such as will enable others skilled in the art to which it appertains to make and use the same, reference being had to the accompanying drawings, and to the letters of reference marked thereon, forming part 15 of this specification.

My invention relates to paper making machines and the object thereof is to provide means and mechanism whereby the water of condensation can be ejected from the 20 drier drums of paper machines without undue loss of steam.

The features of my invention are herein-after fully set forth and pointed out and are illustrated in the accompanying drawings in which:

Figure 1, is a side view partially in section, of a drier drum with my improved mechanism thereon.

Fig. 2, is an end view thereof with one 10 of the journals of said drum in vertical section on the line 2-2 in Fig. 1.

Fig. 3, is a longitudinal vertical section of a drum journal with my improved mechanism thereon.

Fig. 4, is a transverse section on the line 4-4 in Fig. 3.

In these drawings A indicates a drier drum of ordinary construction, being provided with supporting journals A', A'; the heads A² of the drum being provided with cylindrical shoulders A³ in the usual manner. A⁴ indicates the usual longitudinal central opening in one of the journals A' through which steam may be introduced into the drum A.

In carrying out my invention I drill longitudinal ducts B into one of the journals A', which terminate at the periphery of the cylindrical shoulder A³ on opposite sides of the journal A', and within the drum A I place buckets C C at opposite sides of said drum, which buckets are connected by means of tubes D D with the ducts B B in the journal A'.

Secured on the end of the journal A' by means of bolts e, is a cap E which is pro-

vided with holes B', which coincide with the ducts B and with a screw threaded central opening E' in which is secured a pipe F which is concentric with the opening A⁴ 60 in the journal A' and extends forwardly into the drum A, as shown in Figs. 1 and 3.

Secured to the cap E by means of an internally screw threaded collar E² thereon, is a stem G of a ball and socket joint— 65 part G' of the ball thereof being on said stem, and the remaining portion H of said ball being rotatable upon the journal G² of said stem for the purpose hereinafter set forth. The stem G and journal G² are provided with a central longitudinal opening 70 G³ which coincides with the outer end of the tube F. The stem G is also provided with ducts g g which communicate with the ducts B B' in the journal A' and cap 75 E; and the portion of the ball H is provided with a segmental slot H' (see Fig. 4) which communicates with one of the ducts g in the stem G.

Upon the ball portion H I place a housing J which is provided with a duct J' 80 which communicates with the central opening G³ in the stem G and with a duct J² which communicates with the segmental slot H' in the ball portion H.

The housing J being secured in place by means of the housing member K which fits over part of the ball portion H and the ball portion G', and is connected with the housing portion J by means of bolts K 90 which are screwed into openings in the flange J³ in the housing J, and pass through openings in the flange K' on the housing member K, and are provided with springs K² by means of which the housing member 95 K, and the housing member J are drawn toward each other so as to tightly compress the ball G' and H between them.

The ball member H is provided with a hand lever L by means of which the ball 100 member H can be oscillated as desired upon the journal G² of the stem G for the purpose hereinafter set forth.

In operation the drier drums of a paper making machine are rotated in the direction 105 of the arrow in Fig. 2, and steam is introduced thereto through the duct J' in the housing J, and thence through the duct G³ and tube F into the drum, and as the drum rotates the ducts g g in the stem G successively coincide with the segmental slot H' 110 in the ball member H, which communicates

with the exhaust duct J^2 in the housing J , and during the period of such coincidence steam or water of condensation can flow outwardly through the duct B in the journal A , and the duct g in the stem G which coincides with the segmental duct H' and the duct J^2 .

In Fig. 2 by means of broken lines I show the substantial position of the body 10 of water within the drum during the rotation of the drum, and it is well known that the position of this body of water within the drum changes according to the speed of rotation of the drum—i. e. as the speed 15 increases the water is higher up within the drum than when the speed is slow; hence, in order not to waste steam when the bucket C is not in the water the ball portion H acts as a valve to prevent the escape of 20 steam from one of the ducts g while its connected bucket C is not in the water; and as the body of water M within the drum changes its position, it is necessary that the timing of the coincidence of the duct g 25 with the segmental slot H' , or with the exhaust duct J^2 should be advanced or retarded and for this purpose I have provided the ball portion H and made it rotatable with relation to the ball portion G' 30 so that as the drier drum is caused to rotate at the greater speed, the ball portion H having the segmental slot H' therein, is manually rotated to bring the slot H' in substantially the same radial position occupied 35 by the body of water M , so that the duct g will coincide with the slot H' at substantially the same instant that one of the buckets C within the drum A enters the body of water M therein, and the slot H' 40 should be of such width that the duct g will cease to coincide with the slot H' at substantially the same instant that the bucket passes out of the body of water M so that there will be substantially no escape 45 of steam or exhaust out of the duct J^2 when the bucket C is not in the position within the drum A where water will accumulate.

N indicates a pin or bolt adapted to pass through the openings N' in the flanges J^3 50 and K' and through an opening in the handle L to maintain the ball portion H in the desired stationary position, while the stem G continues to rotate in unison with the journal A' of the drum A . In other 55 words, the bolt N maintains the ball portion H in the desired adjustable position with relation to the housing J , while the stem G and ball portion G' continue to rotate.

60 It is apparent therefore, that by means of my improved mechanism the exhaust ducts from the interior of the drier drum will only be open to the atmosphere when the buckets C within the drum are at such 65 a position that the water will be forced out

wardly from the drum through the exhaust duct J^2 .

Having thus fully described my invention so that the same can be utilized by others, what I claim as new and desire to secure 70 by Letters Patent of the United States is:—

1. In a paper making machine a drier drum, axial journals to support the same, means to admit steam into said drum, longitudinal ducts in one of said journals, a tubular connection from each of said ducts to points adjacent to the inner periphery of said drum, and mechanism secured on the end of said journal adapted to open each of 80 said longitudinal ducts alternately to the atmosphere at each revolution of said drum, substantially as set forth.

2. In a paper making machine a drier drum, axial journals to support the same, 85 means to admit steam to said drum, longitudinal ducts in one of said journals, tubular connections from said ducts leading to the inner periphery of said drum and revoluble with said drum, a stem secured on the end of 90 said journal having longitudinal ducts therein which coincide with longitudinal ducts in said journal, and a housing inclosing the end of said stem adapted to open each of said longitudinal ducts alternately 95 to the atmosphere at each revolution of the drum, substantially as set forth.

3. In a drier drum for paper making machines, means within and revoluble with the drum adapted to receive water at each revolution thereof, tubular connections therefrom through the axis of the drum to the atmosphere, means adapted to open and close said tubular connections alternately at each revolution of the drum, means adapted to 105 regulate the timing of said opening and closing, and means to admit steam to said drum during the rotation thereof, substantially as set forth.

4. In a drier drum for paper making machines comprising a drum and axial journals thereon, longitudinal ducts in one of said journals, radial tubular connections revoluble with said drum, leading from said longitudinal ducts to points adjacent to the 115 inner periphery thereof, a central longitudinal opening through said axial journal, a stem secured on the outer end of said journal and revoluble therewith having longitudinal ducts therethrough and a central 120 longitudinal opening therethrough which coincide with the ducts and central opening in said journal, and a housing inclosing the outer end of said stem having a steam inlet 125 passage coinciding with the central longitudinal opening in said stem, and a passage which is adapted to open each of said longitudinal ducts in said stem to the atmosphere at each revolution of said drum and stem, substantially as set forth.

5. In a drier drum for paper making machines, axial supporting journals, a stem secured on the end of one or both of said journals, a central longitudinal opening through said stem and journal, through which steam may be admitted to said drum, longitudinal ducts in said stem and journal eccentric to said central opening, tubular connections leading from said 10 ducts to the interior of said drum, dipper means within said drum and secured adjacent to the inner cylindrical wall thereof and communicating with said tubular con-

nnections, a ball shaped journal on said stem, a housing inclosing said ball shaped journal 15 and having a steam inlet passage coinciding with said central longitudinal opening, and a water and steam outlet passage adapted to coincide alternately with each of said longitudinal ducts at each revolution of said 20 drum, when said dipper means is immersed in water in said drum substantially as set forth.

In testimony whereof I affix my signature.

JOHN C. GLENN.
